WINDOW

Filed Jan. 25, 1927

Fig. 1.

UNITED STATES PATENT OFFICE.

BELONIE CLAVETTE, OF EDMUNDSTON, NEW BRUNSWICK, CANADA, ASSIGNOR OF ONE-HALF INTEREST TO ALPHEE E. LEVESQUE, OF EDMUNDSTON, NEW BRUNSWICK, CANADA.

WINDOW.

Application filed January 25, 1927, Serial No. 163,410, and in Canada March 22, 1928.

Storm windows are extensively used in various sections throughout the country for aiding in keeping the interior of a building comfortable during extremely cold or stormy weather. The type of storm window commonly used must be removed during warm seasons of the year and replaced during cold seasons, as the means for permitting ventilation is limited. Furthermore, this type of storm window usually necessitates the securing thereof to the window frame from the exterior of the building, thus causing considerable inconvenient work at certain periods of the year in order to obtain the desired comfortable living condition within the building.

The present invention relates to storm windows of that particular class which are provided with a double pair of slidable sashes, each pair comprising an upper sash and a lower sash and all the sashes being adjustable to various positions and locked in desired positions for either closing the window or for ventilation, the lower rails of the upper sashes engaging the upper rails of the lower sashes when said sashes are in closed position in order to provide air spaces between the sashes for keeping the cold out of a building having my improved windows therein.

An important object of my invention is the provision of two pair of sashes slidably and detachably mounted in a window frame for permitting the use of a screen in either the top or bottom of the frame, as well as providing easy access to all the panes of glass from the inside for washing, replacing or repairing the same, or for painting the sashes from the inside, and including removable cleats and facings on the left hand side of the frame in order that all sashes may be conveniently removed from the interior of the building.

It is also an object of the invention to provide a window construction of the above indicated character, which is simple and substantial in construction, which can be manufactured economically, and which will be thoroughly efficient and practical in use.

With the foregoing and other objects in view, which will be apparent as the description proceeds, the invention resides in the construction and arrangement of parts, as hereinafter described and claimed, it being

understood that changes can be made within the scope of what is claimed, without departing from the spirit of the invention.

The invention is illustrated in the accompanying drawings, wherein:

Figure 1 is an inside view of my improved window,

Figure 2 is a vertical section taken on line 2—2 of Figure 1,

Figure 3 is a fragmentary vertical section taken on line 3—3 of Figure 1,

Figure 4 is an enlarged vertical section taken on line 4—4 of Figure 3, and

Figure 5 is a view similar to Figure 4, showing the locking element in unlocked position.

In the drawings, the numeral 10 designates a window frame having the usual facing strips 11, sill 12, and cleats 13 for slidably supporting an upper window sash 14 and a lower window sash 15. The above is the usual construction of a window.

Exteriorly of the sashes 14 and 15 in the window frame 10 are slidably mounted another pair of upper and lower sashes 16 and 17, respectively slidably mounted in the frame by means of removable cleats 18. By referring to Figure 2 of the drawings, it will be noted that the two sashes 16 and 17 engage the top and bottom of the window frame 10 when said sashes are in closed position. The two upper sashes 14 and 16 have their bottom strips provided with inclined faces 19 which are adapted to engage inclined faces 20 on the top strips of the lower sashes 15 and 17 so that when all of the sashes are in closed positions air-tight compartments will be provided between the upper sashes and the lower sashes. While opposite inclined faces are provided on the strips of the intermediate sashes an inclined face is formed on the inner side only of the strips of the sashes at opposite sides of said intermediate sashes, the several strips fitting together when the window is closed, as shown in Fig. 2.

Each of the sash is provided with a locking element 21 which consists of a pin 22 slidably arranged in a bore 23 in the sash frame, said bore being enlarged at one end, as at 24, to accommodate a coil spring 25 arranged about the pin 21 and engaging a plate 26 at one end and a washer 27 at the opposite end, said washer being held against sliding move-

ment on the pin 22 by means of a small pin 28 extending through the pin 22. The pin 22 extends through the plate 26 and has pivotally connected thereto a lever 29, said lever 5 having a hand engaging portion 30 at one end and a forked portion 31 at the opposite end, the opposite side portions of said forked end being at opposite sides of the pin 22 and pivotally connected to the pin by means of a 10 pivot pin 32 extending through said side portions and through said pin 22. The side portions of the forked lever protrude a slight distance beyond the point of pivot so that when said lever is swung upon said pivot, the ends 15 of said side portions will engage the plate 26 and cause the pin 22 to be slid in the bore 23 against tension of the coil spring 24. The window frame 10 has provided therein at spaced intervals a series of sockets 35 into 20 which the pins 22 are adapted to engage in order to lock the sashes in various positions. It is to be noted that the locking elements are located in the side rails of the sashes at the inner side of the window panes for convenient 25 manipulation in locking and unlocking the sashes from the inside of the window frame.

In operation, any one or more of the sashes may be slid within the window frame in order to open the window as desired, the 30 locking means being manipulated by the hand engaging portion 30 of the lever 29 on the sash to be opened and swinging said lever to a position such as that indicated in Figure 35 5, when the pin 22 will be drawn from the opening 35 in the window frame. The sashes have attached thereto the usual weights (not shown) in order that the sashes will remain in the positions they are left in when unlocked. When it is desired to lock a sash in a 40 certain position it is slightly moved until one of the openings 35 aligns with the pin 22 and the pin released by swinging the lever 29 to

a position such as that indicated in Figure 4 of the official drawings.

It is to be noted that I have not provided a 45 temporary storm window, but have arranged in the window frame two pair of sashes which are of permanent construction and remain in the window frame at all times. It can also be seen that the sashes may be moved to different positions in the window frame in order to provide a maximum size opening through the window. By sliding the sashes access may be gained to both sides of all 50 of the sashes so as to permit repairing or painting of all sashes. The cleats are arranged so that the ones on the left hand side may be conveniently removed in order to remove the sashes, thus permitting a person 55 removing or replacing a sash to do so from within the building. By arranging the sashes so that the uppermost of one pair engages the lowermost of the other pair, two air spaces are provided, which will permit the retaining of one air space should a pane 60 of glass forming a wall of the other air space be broken or otherwise rendered inefficient.

Having thus described my invention, what I claim as new is:

A device of the character described comprising a window frame, a pair of sashes slidably mounted in said window frame, said pair of sashes consisting of an upper sash and a lower sash for closing the window opening, and another pair of sashes slidably arranged in said window frame exteriorly of said first mentioned pair and consisting of an upper sash and a lower sash, the upper sashes of both pair being adapted to engage 75 the lower sashes when said sashes are in closed position to provide separate air spaces. 80

BELONIE CLAVETTE.
